UNITED STATES PATENT OFFICE

95,206

DESIGN FOR A VACUUM CLEANER CASING

David Hays, Fairfield, Conn., assignor to General
Electric Company, a corporation of New York

Application October 23, 1934, Serial No. 53,727

Term of patent 14 years

To all whom it may concern:

Be it known that I, David Hays, a citizen of the United States, residing at Fairfield, in the county of Fairfield and State of Connecticut, have invented a new, original, and ornamental Design for a Vacuum Cleaner Casing, of which the following is a specification, reference being had to the accompanying drawing, forming part thereof.

The figure is a perspective view of a vacuum cleaner casing showing my new design.

I claim:

The ornamental design for a vacuum cleaner casing, as shown.

In witness whereof, I have hereunto set my hand.

DAVID HAYS.
